UNITED STATES PATENT OFFICE.

ERNEST HENRY STILL, OF LONDON, ENGLAND.

GRENADE.

1,172,498.

Specification of Letters Patent. Patented Feb. 22, 1916.

Application filed March 27, 1915. Serial No. 17,373.

To all whom it may concern:

Be it known that I, ERNEST HENRY STILL, a subject of the King of Great Britain and Ireland, residing at Hatton Garden, in the city of London, England, have invented Improvements in Grenades, of which the following is a specification.

This invention has reference to hand grenades, the object being to reduce the danger 10 of premature explosion due to the grenade being dropped or other cause.

In a hand grenade according to this invention the striker is normally held inoperative by means which by the action of throwing 15 the grenades are caused to free the striker previous to the grenade being released from the hand.

The accompanying drawing illustrates in longitudinal section such a hand grenade.

20 In the arrangement according to the figure, the body 1 of the grenade, containing the charge (not shown) and the detonator, has in line with the detonator tube 2 a tubular shank 3 containing at its inner part a 25 time fuse 4 provided with the usual percussion cap 5 or priming and at its outer part a striker 6 which is pressed forward by a spring 7 and extends through a plug 8 in the end of the shank and is there connected to a 30 sleeve 9 that passes over the outer portion of the shank and is formed as a hand grip.

In the example the shank is in two parts, the inner part, containing the time fuse 4, being screwed into the enlarged head of the 35 detonator tube 2 and the outer part, containing the striker 6, fitting on to the inner part and being fixed thereto by screws 10 as shown. The striker 6 and connected hand grip sleeve 9 are held so that the nose of the 40 striker is clear of the cap or priming 5 by a spring or springs 11 which engages or engage with the inner end of the hand grip, or with the inner end of the striker, or with both, and is or are prevented from spring- 45 ing out of engagement therewith by the hand grip or the striker or both.

Conveniently the retaining springs 11 may be in the form of suitably shaped leaf springs as shown and be attached by the 50 screws 10 to the outside of the shank at its inner part, their outer ends tending to spring outward into the positions shown in dotted lines; each spring is formed with an outwardly projecting portion 11^a against which 55 the inner end of the hand grip sleeve 9 abuts and beyond said projecting portion with a

part that is overlapped as shown by the said sleeve and that has an inwardly turned end 11^b that extends through a hole 12 in the shank wall and engages the front of the 60 piston-like head of the striker. The forward or inner end portion of the sleeve is enlarged where it overlaps the springs. The arrangement is such that on the hand grip sleeve 9 being seized and the grenade there- 65 by swung in the act of throwing it, the force exerted by the body 1 will draw the shank forward in relation to the hand grip sleeve 9 and striker 6 against the action of the spring 7; the retaining spring or springs 11 70 will then automatically assume the dotted position and disengage the hand grip sleeve and striker and, as soon as the hand grenade is released from the hand of the thrower, the striker will be forced forward 75 by its spring 7 against the cap or priming 5 which will ignite the time fuse.

A safety pin 13 may be passed transversely through holes in the hand grip sleeve and the shank between the cap and the 80 striker so as to prevent accidental release of the striker during transport. The hand grip sleeve is shown provided with a wooden knob at its outer end to enable it to be more securely gripped. 85

As will be understood instead of a time fuse adapted to be ignited during flight by a spring propelled striker, a striker which, owing to inertia, will act on a detonator upon impact of the grenade, may be employed. The striker between which and the detonator is interposed a light spring, may then be formed with a groove into which the ends 11^b of the retaining springs 11 project while held by the sleeve 9, which 95 overlaps them; in this arrangement the striker is not connected to the forwardly spring-pressed hand-grip sleeve 9.

A grenade of the kind described being dependent on the act of throwing for release 100 of the striker is comparatively safe to handle and its effective action is not liable to be affected by wind conditions as is the case with grenades in which release of the striker is effected during flight by vanes or the like. 105

What I claim is:—

1. A hand grenade comprising a charge container, a striker movable in relation thereto and means adapted normally to hold the striker inoperative and, by the action of 110 throwing, to free the striker previous to the grenade being released from the hand.

2. A hand grenade comprising a charge container, a tubular shank connected thereto, a striker within such shank, a hand grip sleeve and obstructing means controlled thereby, such means being adapted to prevent movement of the striker while the hand grip sleeve is in one position and to release the striker when such hand grip sleeve occupies another position to which it moves automatically in the act of throwing the grenade.
3. A hand grenade comprising a charge container, a tubular shank connected thereto, a striker within such shank adapted to move toward the charge container, a movable hand grip sleeve surrounding said shank and to which the striker is connected so as to move therewith, and obstructing means adapted to prevent movement of the striker toward the charge container while the hand grip sleeve is in one position and until after the said sleeve has occupied another position to which it moves automatically in the act of throwing the grenade.
4. A hand grenade comprising a charge container, a tubular shank connected thereto, a striker within such shank, a spring urging the striker toward the charge container, means adapted to obstruct the striker and a hand grip sleeve having a portion adapted to normally overlap the striker obstructing means, the said hand grip sleeve being adapted to recede to release the obstructing means previous to the grenade being released from the hand.
5. A hand grenade comprising a charge container, a tubular shank pierced intermediate of its length and connected thereto, a striker within such shank, a movable hand grip sleeve surrounding said shank and to which the striker is connected, a spring urging the striker toward the charge container and springs connected to the exterior of the tubular shank and having extremities protruding through the piercings in such shank, so as to engage the striker, the said springs being normally held in engagement by the hand grip sleeve a portion whereof is adapted to overlap the springs and recedes to liberate the springs previous to the grenade being released from the hand.
6. A hand grenade comprising a charge container, a striker movable in relation thereto, a hand grip sleeve to which the striker is connected, means urging the striker

and sleeve toward the charge container and spring means adapted to be overlapped by a portion of the sleeve so that such means is normally held in a position to serve as an abutment to resist movement of the sleeve and striker toward the charge container and from which position such spring means moves automatically upon relative recession of the sleeve in the act of throwing the grenade, thereby permitting a subsequent unobstructed advance of the sleeve and striker.

7. A hand grenade comprising a charge container, a striker movable in relation thereto, a guide for such striker, a spring controlling movement of the striker, a hand grip sleeve movable in relation to the grenade and means adapted to be overlapped by a portion of the sleeve so that such means is normally held in a position obstructing the striker the said overlapping portion automatically releasing the obstructing means in the act of throwing the grenade.

8. A hand grenade comprising a charge container, a tubular shank pierced intermediate of its length and connected thereto, a striker within such shank, a movable hand grip sleeve surrounding said shank and to which the striker is connected, a spring urging the striker toward the charge container and springs connected to the exterior of the tubular shank, such springs having extremities protruding through the piercings in the said shank so as to enter the path of the striker and also having shoulders leaving portions adapted to be overlapped by a portion of the hand grip sleeve.

9. In a hand grenade, the combination with a charge container, of a tubular and pierced shank forming an extension of the container, a striker housed in such tubular extension, blade springs attached to the extension and having shouldered ends passing through the pierced portions of the extension so as to engage the striker and a sleeve device overlapping the shouldered ends of the springs aforesaid, the said springs being freely exposed to permit them to be held by hand while the overlapping sleeve device is being moved into engagement therewith.

Signed at London, England, this 19th day of March, 1915.

ERNEST HENRY STILL.
